C. HARDY

FOUNTAIN PEN CLIP

Filed July 11, 1924

Patented Nov. 17, 1925.

1,562,326

UNITED STATES PATENT OFFICE.

CHARLES HARDY, OF NEW YORK, N. Y., ASSIGNOR TO AMSCO PRODUCTS, INC., OF NEW YORK, N. Y., A CORPORATION OF NEW YORK.

FOUNTAIN-PEN CLIP.

Application filed July 11, 1924. Serial No. 725,360.

To all whom it may concern:

Be it known that I, CHARLES HARDY, a citizen of the United States, and resident of New York, in the county of New York and State of New York, have invented certain new and useful Improvements in Fountain-Pen Clips, of which the following is a specification.

This invention relates to a fountain pen clip and its means of attachment.

While the invention may be applied to articles other than fountain pens, it will be discussed herein as intended for use upon a fountain pen cap, and with this in mind, it is stated that an object of the invention is to provide a clip which is of simple and strong construction and which may be attached to the cap of a fountain pen or the equivalent, by means which is integral with the clip and provides a strong and substantial connection without appreciably increasing the cost of the clip.

A further object is to provide a clip which is formed of a single piece of sheet metal having portions of itself so shaped and bent as to provide tangs adapted to project inwardly through openings of the pen cap, one of said tangs being relatively short and being adapted to hold its adjacent portion of the clip against lateral movement relative to the cap and another tang being relatively longer and being adapted at once to hold its respective portion of the clip against lateral movement and to retain the first mentioned tang in effective holding position.

A further object is to so design the clip that a single bendable tang will be sufficient to hold the clip in firm engagement with the cap.

Other objects and aims of the invention more or less specific than those referred to above, will be in part obvious and in part pointed out in the course of the following description of the elements, combinations, arrangements of parts, and applications of principles constituting the invention, and the scope of protection contemplated will be indicated in the appended claims.

In the accompanying drawings which are to be taken as a part of this specification and in which I shall show merely a preferred form of embodiment of the invention:

Fig. 1. is a side elevational view of a portion of a fountain pen having a cap thereon fitted with a clip device constructed in accordance with this invention, parts being illustrated in vertical section for the disclosure of details. 55

Fig. 2. is a top plan view of the pen cap seen in Fig. 1, the clip being removed. 60

Fig. 3. is a side elevational view of the clip appearing in Fig. 1, the clip being here illustrated in its normal position before attachment to the cap and a part being shown 65 in section for better disclosure of details, and

Fig. 4. is a top plan view of the clip seen in Fig. 3.

Referring to the drawings for describing 70 in detail the structure shown therein, the reference character L indicates an ordinary fountain pen barrel to which is connected the usual cap or guard member G, the same being herein shown as being threaded upon 75 the barrel as at 1 in accordance with the usual present-day practice.

Within the cap G is fixed the usual tubular member 2 serving to reinforce the cap and providing a shoulder 3 adapted to rest against the shoulder portion (4) of the pen for limiting the thread movement of the cap and thereby properly guarding the pen point portion 5 of the pen against injury, 80 etc. 85

The clip is indicated generally by the reference character H. It is made from a single piece of sheet metal of appropriate contour providing what may be termed the body portion 6 and a spring portion 7, the usual friction ball as 8 being at the extreme 90 end of the portion 7.

The body portion 6 is shaped to lie snugly against the outer curved surface of the cap and has two tangs as 9 and 10 integral 95 therewith, the tang 9 being at or near the rear end of the body and the tang 10 being at or near the forward end of the body. These tangs are both bent at approximately right angles to the body and are adapted to 100 extend through a pair of mating apertures 11 and 12 respectively provided in the cap.

The tang 9 is relatively short and in the instance illustrated, is formed by bending over a continued or projecting portion of 105 the body 6. It is of such size relative to

the aperture 11 as to have a snug fit in said aperture, and its length is preferably not greater than the thickness of the cap wall.

5 The tang 10 is of considerably greater length than the tang 9 and its inner end portion as 13 is bent rearwardly at an acute angle, the portion as 14 of said tang which remains at right angles to the body portion 6 of the clip being substantially equal to the

10 thickness of the cap wall or slightly less. This tang is stamped out from the material of the body as most clearly illustrated in Figs. 3 and 4 so that it stands aligned with the tang 9.

15 In its normal condition as seen in Fig. 3, this clip has its central portion bowed upwardly with respect to a straight line as 15, extending from the under surface of the ball 8 to the under surface of the rear end

20 of the body 6. When being applied, however, onto the pen cap, the end of the tang 10 is moved through the aperture 12, the tang 9 is introduced into the aperture 11 and pressure is exerted to spring the upwardly

25 bowed portion downwardly into a straightened condition so as to bring the body 6 into a close contact with the surface of the cap throughout the extent of said body, as in Fig. 1, and so as to cause a suitable spring pressure of the ball and of the opposite end of the clip against the cap.

While the clip is held in this position, the tubular part 2 is inserted and, coming into engagement with the already bent inner end portion 13 of the tang 10, easily bends said inner portion 13 backwardly and clamps it tightly between the inner surface of the cap and the outer surface of the tubular reinforcing liner member 2 and this locks the clip against return to its normal bowed condition.

It is important to note in connection with this structure:

45 1st. That the tang 10 being connected with the normally upwardly bowed central portion of the clip serves to hold the opposite end portions of the clip resiliently against the surface of the cap.

50 2nd. That the tang 9 on the rear end portion, and fitting snugly into the aperture 11, is made to cooperate with the tang 10 for holding the clip against possibility of movement in all directions.

55 3rd. That by shaping the tang 10 with its inner end portion normally inclined towards its final locking position the effort required to complete its bending to locking position is materially reduced, and that also a grade of sheet metal suitably thick for forming the main portion of the clip will also be usable for forming the tang and thus render it entirely practical to make said tang integral with the remainder of the clip.

60 65 To further facilitate the bending of the

inner portion 13 of the tang 10, the tubular part 2 may be cut away so as to provide a shoulder 16 at its rear end disposed so that when said tubular part is being inserted into the cap, said shoulder will engage the portion 13 at a point sufficiently near the inner end of the portion 13 to acquire a desirable amount of leverage against the tang.

70 75 4th. That by so shaping the tang 10 that in its normal condition the point of bend, as indicated by the reference numeral 17 in said tang, is slightly less far from the inner surface of the body 6 than the thickness of the cap wall the act of bending the projecting inner end of the tang by engagement of the 80 part 2 will produce a crowding effect upon the interposed wall portion of the cap and afford a degree of leverage which will operate to force the body 6 into tight engagement with the outer surface of cap.

85 90 5th. That by striking out the tang 10 from the material of the body 6 and thus leaving an opening 18 longitudinally of the body only relatively thin strips as 19 of the body are left on opposite sides of said opening, which because of their reduced size are suitably flexible to facilitate a desirably slight degree of bending of the body particularly during the operation of attaching the clip onto the pen cap, thus making it possible to dispose the portion 13 of the tang 10 normally at a more acute angle than it could otherwise be. This resiliency or flexibility of the body also lends a desirable added 95 flexibility to the operation of the clip in use, while at the same time always holding the tang 9 in snug engagement with the aperture 11.

100 105 While the drawings herein illustrate the present clip as being connected to a pen cap of the usual molded type, yet it will be understood, however, that it can be used with equal facility upon pen caps or the like of thin sheet metal construction, the only difference in this case being differences in degree.

110 115 As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention what I claim is new and desire to secure by Letters Patent is:

120 125 1. A pen clip comprising, a body portion having the usual spring extension, a pair of tangs provided upon said body portion for use in attaching the body portion to the pen cap, at least one of said tangs being adapted to extend through a suitable aperture of the pen cap and to be bent over internally of the pen cap, and said mentioned tang having 130

at least a portion of itself bent to stand normally at an acute angle to the longitudinal plane of said clip so as thereby to facilitate the further bending of said tang when attaching the clip to the pen cap.

- 5 2. A pen clip formed from a single strip of sheet metal having a body portion at one end and a friction ball at the other end, a tang provided upon said body adapted to enter a suitable opening in the pen cap, said 10 tang being at the extreme end of said strip, and a second tang aligned with the first tang longitudinally of the strip adapted to engage the pen cap to thereby cooperate with the first tang for retaining the clip firmly 15 attached to the cap, and said second tang comprising, a part struck out from the material of the body portion.

3. A pen clip comprising, a body portion 20 having the usual spring extension, a tang provided upon said body portion for use in attaching the body portion to a pen cap, said tang being adapted to extend through a suitable aperture in the pen cap and to be bent 25 over internally of the pen cap, and said tang having at least a portion of itself bent to stand normally at an acute angle to the longitudinal plane of the clip so as to thereby facilitate the further bending of said 30 tang when attaching the clip to the pen cap.

4. A pen clip comprising, a body portion 35 having the usual spring extension, a tang provided upon said body portion for use in attaching the body portion to a pen cap, said tang being adapted to extend through a suitable aperture in the pen cap and to be bent 40 over internally of the pen cap, said tang having a portion of its length disposed substantially at right angles to the longitudinal plane of the clip and adapted to

stand within the aperture of the pen cap, and said tang having the remainder of its length bent at an acute angle to the longitudinal plane of the clip adapted to project into the interior of the cap, the angular disposition of said second portion of the tang 45 serving to facilitate the further bending of the tang when attaching the clip to the pen cap.

5. The combination with a cap of the 50 type indicated, of a clip therefor comprising a body portion having the usual spring extension part, two tangs extending from said body portion into openings provided to receive them in the wall of the cap, one of said tangs being bendable and being normally projecting into the interior of the cap in a direction away from the body of the clip, together with a liner member forming part of said cap and adapted upon insertion into the cap to engage and bend said tang and hold said tang bent into substantial parallelism with the body of the clip.

6. The combination with a cap of the class 55 described, of a clip therefor formed from a single strip of sheet metal having a body portion at one end and a friction ball at the opposite end, said clip being normally bowed upwardly intermediate its ends, a pair of tangs formed as integral extensions 60 of the body portion arranged to project into spaced openings of the cap, and one of said tangs serving to hold the clip sprung into straightened condition and to utilize the force thus generated for holding the second tang in engagement within its respective 65 opening.

In testimony whereof I affix my signature.

CHARLES HARDY.
